US00D768241S

(12) **United States Design Patent** (10) **Patent No.:** **US D768,241 S**
Bull et al. (45) **Date of Patent:** **** Oct. 4, 2016**

(54) **LABEL SET FOR AN INHALATION DEVICE**

(71) Applicant: **Glaxo Group Limited**, Brentford, Middlesex (GB)

(72) Inventors: **William Bull**, Ware (GB); **Richard Adams**, Research Triangle Park, NC (US); **Philippe Ragot**, Research Triangle Park, NC (US); **Carlo Brunelli**, Verona (IT); **Lisa Olivieri**, Verona (IT); **Jeffrey Schons**, Research Triangle Park, NC (US); **Alec Johnson**, Barnard Castle (GB)

(73) Assignee: **Glaxo Group Limited**, Brentford, Middlesex (GB)

(**) Term: **15 Years**

(21) Appl. No.: **29/542,535**

(22) Filed: **Oct. 15, 2015**

Related U.S. Application Data

(63) Continuation of application No. 29/469,595, filed on Oct. 11, 2013, now abandoned.
